BY E. J. Getheronhaugh
ATTORNEY

UNITED STATES PATENT OFFICE.

JOSEPH ANTONIO DUFRESNE, OF MONTREAL, QUEBEC, CANADA.

LOCK.

Application filed April 24, 1923. Serial No. 634,380.

To all whom it may concern:

Be it known that I, JOSEPH ANTONIO DUFRESNE, a subject of the King of Great Britain, and residing at 348 St. Denis Street, 5 apartment No. 21, in the city of Montreal, in the Province of Quebec, in the Dominion of Canada, have invented a new and useful Lock, of which the following is the specification.

10 The invention relates to a lock, as described in the present specification and shown in the accompanying drawings that form part of the same.

15 The invention consists essentially of the novel features pointed out broadly and specifically in the claims for novelty following a description containing an explanation in detail of an acceptable form of the invention.

20 The objects of the invention are to avoid felonious interference with locks in hotels, public buildings and other places, where the cylinder mortise-locks are used; to insure safety to occupants of buildings by furnishing a lock to a lock operable only by the person interested; to positively prevent the removal of a lock from its position by other than the possessor of the auxiliary key; and generally to provide in locks a safety device, 25 whereby unlawful entrances can be avoided, and to do this without materially adding to the cost of production.

In the drawings, Figure 1 is a side elevation of a mortise-lock casing and front plate, 35 broken away and sectioned to disclose the features of this invention.

Figure 2 is an elevation of the front plate, showing the auxiliary lock.

Figure 3 is a perspective detail of the operating screw and discs.

Figure 4 is a perspective detail of the locking bolt member.

Like numerals of reference indicate corresponding parts in the various figures.

45 Referring to the drawings, the cylinder 1 is shown as screwed into the lock casing 2 as usual and projects outwardly therefrom as usual to reach through the thickness of the door and inwardly through said casing, having the locking bolt slot 3 across the threads to the extreme inner end within said casing 2.

50 This feature as described is not novel as these cylinder locks are nearly all made with the slot across the threads longitudinally arranged with the cylinder, and the customary

way of operating the locking bolt member is by means of a screw turned from the front plate and this is also done in the present instance, in which the locking bolt 4 projects from the body 5 at the upper end and a similarly shaped guide bar 6 projects from the lower end, both the bolt 4 and bar 6 sliding in corresponding slots in the casing 2, said body 5 being centrally slotted at 7 and having the screw hole 8 through the end wall of said slot.

The operating screw 9 is screwed into body 5 in the hole 8 and projects through to the slot 7 during the operation thereof and is formed with the square head 9a. The disc 10 fits closely to the stem of the screw 9 and has the two screw holes 11 and 12 and the disc 13 in its square central slot 14 fits closely to the head 15.

75 The barrel 16 of the auxiliary lock turns in the cylinder 17 and has the longitudinal key slot 18 shaped to suit the wards of the particular key used and this slot 18 crosses the lower ends of the tumbler pin holes 19 in which the pins 20 are inserted over the balls 21.

The pin case 22 extends from the cylinder 17 and has corresponding pin holes 23 to the pin holes 19 and pins 24 in said holes 23, which are held down to their engagement with the pins 20 by the springs 25.

80 The cylinder 17 and pin case 22 form one rigid member and are secured within the casing 2 opposite to the cylinder 1 and immediately behind the plate 26, and in alignment with the hole 27 in said plate. The pin case 22 rests on a boss and is secured thereto by the screw 28 and abuts the boss 29, so that it is firmly held in place.

95 The discs 10 and 13 are secured to the barrel 16 by the screws 30 and 31 and as the disc 10 abuts the cylinder 17 and pin case 22 the barrel is securely held in said cylinder and further the square head of the operating screw 9 being held between the barrel 16 and disc 13, the auxiliary lock and operating screw together form the operating member for inserting and withdrawing the locking bolt 4.

100 The insertion of the key 32 registering with the combination of the pins 20 and 24 brings them in a position where the split between the case pins and barrel pins permits the free rotation of the barrel by means of the key and consequently the rotation of the screw 9, therefore the only way that the

main cylinder can be removed from the casing 2 by inserting the key in the auxiliary lock and drawing the locking bolt member and locking bolt away from said main cylinder, leaving the latter free to be unscrewed so as to free the casing in order that it may be removed from its recess in the door for changing its combination or repair work.

10 This auxiliary lock makes it next to impossible for persons of bad character to tamper with locks in hotels or other places in the absence of the occupant or owner, as the open door offers no facilities in the way of removing and changing the lock mechanism, because it is always necessary to have the additional key to reach the main lock for removal.

Further it must be pointed out that the provision of this auxiliary lock prevents the finding of the master key combination and also removing and taking away the lock.

What I claim is:—

1. In a lock, a lock casing and a removable member projecting into said casing and fastened therewithin, and an auxiliary lock forming an operating member for securing and releasing the fastening of said removable member.

2. In a lock, a lock casing and a key member adapted to secure said casing within a closure, a fastening for said key member within said closure, and an auxiliary lock for operating said fastening.

3. In a lock, a lock casing and a key member secured therein and removable therefrom, a sliding member engaging said key member within said casing, and an auxiliary lock having a suitable operating member projecting therefrom to said sliding member.

4. In a lock, a lock casing and a key member screwed into said casing and projecting outwardly therefrom, a sliding member and an auxiliary lock having an operating screw projection engaging said sliding member.

5. In a lock, a lock casing and a cylindrical key member screwing into said casing and slotted, a locking bolt member slidably arranged in said casing and having a locking bolt projecting into the cylinder

slot, an operating screw engaging said locking bolt member and an auxiliary barrel and cylinder lock engaging said screw for operating said locking bolt member.

6. In a lock, a mortise-lock casing and a cylinder and barrel key member screwing into said casing through the lock recess wall and slotted across the threads, a locking bolt member, slidably arranged in said casing and having a locking bolt projecting into the cylinder slot, an operating screw engaging said locking bolt member and an auxiliary barrel and cylinder lock engaging said screw for operating said locking bolt member.

7. In a lock, a lock casing and a cylindrical key member screwing into said casing and slotted, a locking bolt member having a centrally slotted body and screw hole in the outer wall of said slot and a lug forming a locking bolt and a similar lug forming a guide and an auxiliary lock having a screw engaging said locking bolt member in said screw hole.

8. In a lock, a lock casing and a cylindrical key member screwing into said casing and slotted, a locking bolt member slidably arranged in said casing and having a locking bolt projecting into the cylinder slot, an operating screw having a square head, a disc mounted on said screw and held by a locking disc, and an auxiliary lock having a barrel member secured to said discs and adapted to operate said screw.

9. In a lock, a lock casing and a cylindrical key member screwing into said casing and slotted, a locking bolt member slidably arranged in said casing and having a locking bolt projecting into the cylinder slot, an operating screw engaging said locking bolt member and an auxiliary lock secured within said casing and having a barrel member projecting through the front plate and having discs at its inner end holding it in the cylinder and operatively connected to said screw.

Signed at Montreal, Canada, this 21st, day of April, 1923.

JOSEPH ANTONIO DUFRESNE.
